Specification for Design.

Patented May 10, 1921.

Application filed November 29, 1918. Serial No. 264,743. Term of patent 14 years.

To all whom it may concern:

Be it known that we, RUDOLPH J. BOURGEOIS and GEORGE P. ITTIG, citizens of the United States, residing at Chicago, in the county of Cook and State of Illinois, and at Bridgeport, in the county of Fairfield and State of Connecticut, respectively, have invented a new, original, and ornamental Design for Percolators, Urns, and Similar Articles, of which the following is a specification, reference being had to the accompanying drawings, forming part thereof.

The Figure 1 is a plan view of a coffee percolator, showing our new design.

The Fig. 2 is a side elevation of the same.

We claim:

The ornamental design for a percolator, urn, or similar article, as shown.

RUDOLPH J. BOURGEOIS.
